MACHINE FOR SETTING OR DRIVING
RIVETS AND THE LIKE

William Carlyle Dent, Birmingham, England, assignor to Baxters (Bolts, Screws & Rivets) Limited, Birmingham, England

Application July 25, 1941, Serial No. 404,016
In Great Britain July 26, 1940

2 Claims. (Cl. 78—48)

This invention relates to machines for setting or driving rivets and the like, being of the kind in which the said rivets or the like are fed in succession to a pocket or holding device for operation upon by a setting or driving tool, the pocket comprising a pair of jaws carried by angularly-movable members acted upon by a spring tending to close the jaws to grip a rivet between them.

One of the objects of the present invention is to provide improved means for releasing the rivet from the pocket at the time of setting the rivet whereby wear of the pocket and plunger is avoided.

Another object is to avoid the formation of a flash or rim around the head of the rivet during the setting operation, especially in the case of countersunk or flush rivets.

According to the invention, the jaws of the pocket are positively opened, prior to the setting operation, by means of the ram or tool acting upon the angularly-movable members carrying said jaws. This positive opening of the pocket obviates the wear upon both plunger and pockets which is occasioned when the tool forces the rivet from the pocket during the setting operation, as is the usual practice. The pocket carrying members may have opposed arms, projections or cam surfaces adapted to be engaged by a conical part on the ram or tool, whereby the pocket jaws are spread apart prior to the setting operation.

The tool has a lower end of larger diameter than the head of the rivet to be set, to avoid the formation of a flash or rim on the surface of the head, and it contains a spring-pressed plunger which, after the opening of the pocket, engages the rivet prior to the main tool fully descending to set the rivet.

Figure 1 of the accompanying drawings is a side elevation of one form of the invention showing the setting tool and the pocket at the top of their travel, the pocket being in a position to receive a rivet from the chute.

Figure 2 is a similar view when the setting tool is fully lowered.

Figure 3 is a front elevation with the pocket and tool in the positions represented in Figure 1.

Figure 4 is a plan of the pocket.

Figure 5 is a vertical section through the setting tool, when raised, on a larger scale.

Figure 6 is a vertical section through the setting tool when lowered on to the work, also on a larger scale.

Referring to the drawings, the riveting ma-

chine may be of any general construction, for example, as described in my application Serial No. 402,362. A vertically-sliding ram carries a setting tool 1 arranged to co-operate with a stationary anvil 2 upon which the work 3 is placed. The rivets are fed from a hopper into a chute 4 (Figure 3) which delivers them one at a time to a pocket or holder 5. This pocket 5 consists of two recessed separable jaw parts, each of half cup form, adapted to receive and rigidly grip a rivet between their lower ends. These pocket parts are carried by arms 6 secured upon the lower ends of vertical shouldered carrier rods or pins 7 which are rotatably mounted to turn, at their upper ends, within bearing holes in a block 8 secured to the underside of an angle-shaped plate 9 and to turn, by their shouldered lower ends, within bearing holes in a cross-head 10 attached to the lower end of a depending part 11 of said block 8. Fixed to the pins 7 are arms 12, 12, the outer ends of which embrace the shank of tool 1 and which are connected by a spring 13 (Figure 4) that maintains them against said shank and tends to close the pocket parts 5 together so as to grip a rivet between them. The angle-shaped plate 9 constitutes a pocket carrier or slide and is adapted to be raised and lowered, being vertically guided by two rods 14, 15, attached to the plate and slidable in passages 16, 17, in the guide block 18 of the machine frame. One of the rods may be acted upon by a spring (not shown) that tends to raise the pocket, and it is adapted to be acted upon by pedal-operated mechanism, as described in my said application Serial No. 402,362, in order to lower the pocket to take a rivet to the work. Upon the shank of tool 1 is adjustably fixed a collar 20 having a conical lower end 21 which cooperates with the arms 12 of the pocket carrier to cause the parts of the pocket 5 to separate to release the rivet when the tool descends (Figure 2) and to slightly open the said pocket to receive a fresh rivet from the chute 4 when the pocket rises (Figures 1 and 3). Thus, after the pocket has been lowered to cause a rivet to be partially inserted into the holes of the work components 3, the tool 1 descends and the conical end 21 of the collar 20 thereon engages the arms 12, thus spreading them apart and causing the two parts of the pocket 5 to separate and thereby release their grip upon the rivet. As the tool further descends its lower end engages the rivet head and in co-operation with the anvil 2 effects the setting of the rivet.

(Figure 2). When the tool rises the pocket follows it, being raised by the spring, and coming to rest with the arms 12 just engaging the cone 21 so as to open the pocket just sufficiently to receive a rivet from the chute 4 (Figure 3).

The setting tool 1 has a flat bottom face of considerably larger diameter than the head of the rivet to be set. The tool is bored from its lower end with an axial hole (Figures 5 and 6), and fitted therein is a plunger 22 which normally projects (Figure 5) from the said lower end of the tool, being thrust downwards by a spring 23. This plunger 22 engages the rivet head as the pocket parts 5 are opened and before the main part 1 of the tool contacts with the rivet, so as to thrust the rivet fully into the hole and hold it firmly in position. As the tool descends further, its main part moves relatively over the stationary plunger 22 until its end face is flush with the end of the plunger and in engagement with the rivet (Figure 6), when the inner end of the plunger engages a stop 24, so that the plunger and main tool act as a solid unit for effecting the actual setting of the rivet; and as the end of the main tool 1 is of considerably larger diameter than the rivet head, the latter is forced into the countersink of the hole with its top face perfectly flat, without any flash and without any distortion of the work, and flush with the top surface of the work. The tool and plunger, however, may be shaped to form a head of a domed or other shape.

I claim:

1. A machine for driving or setting rivets or the like comprising a driving or setting tool pro-

vided with a downwardly-presented conical part, a vertically-movable pocket carrier, a pocket for holding a rivet consisting of spring-pressed jaws, and angularly-movable members carrying the pocket jaws and mounted on the pocket carrier, the conical part of the tool co-operating with the angularly-movable members when the tool and pocket are raised in order to cause the pocket to open slightly to receive a rivet and also acting on said angularly-movable members when the tool descends and the pocket has been lowered, in order to open the pocket and release the rivet therein prior to the tool engaging the rivet.

2. A machine for driving or setting rivets and the like comprising a driving or setting tool provided with a downwardly-presented conical part located on its shank at a point above the operative lower end of the tool; a fixed frame, a slide member vertically guided in said frame; a bracket depending from the slide; a pair of spaced vertical rods rotatably mounted in the depending bracket; a pair of arms extending from the lower ends of the respective vertical rods; opposed pocket jaws carried by the outer ends of the arms, being adapted to receive and hold a rivet or the like between them; a pair of spaced upper horizontal arms attached to the vertical rods and embracing the tool shank, being adapted to be engaged and spread apart by the cone, when the tool descends and the pocket jaws have been lowered, in order to open said jaws and release the rivet therein prior to the tool engaging the work; and a spring acting on the upper horizontal arms and tending to close them about the tool shank.

WILLIAM CARLYLE DENT.
